COMBINED DISPLAY PACKAGE AND CORELESS ROLL DISPENSER

Myer Gorman, Fort Lee, N.J., assignor to Sun Chemical Corporation, New York, N.Y., a corporation of Delaware

Filed Feb. 19, 1968, Ser. No. 10,629

Term of patent 14 years

Int. Cl. D9—04

U.S. Cl. D9—187

FIG. 1 is a front elevation of a combined display package and coreless roll dispenser, showing my new design;

FIG. 2 is a rear elevation of the coreless roll dispenser thereof with the broken line showing of the display card and rolls having been omitted for convenience of illustration; and

FIG. 3 is a side elevation as viewed from the line 3—3 of FIG. 2.

The dominant features of my design reside in the full line portions.

I claim:

The ornamental design for a combined display package

and coreless roll dispenser, substantially as shown and described.
